GAS PRODUCER

Filed Jan. 9, 1928

UNITED STATES PATENT OFFICE

PHILIP S. HULT, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

GAS PRODUCER

Application filed January 9, 1928. Serial No. 245,461.

The present invention relates to gas producers, and has particular reference to the disposition and support, in a rotary gas producer, of the main fuel-containing section or shell.

The invention involves certain structural improvements in the type of rotary gas producer shown and described in United States Letters Patent to Jefferies, No. 1,255,015, dated January 29, 1918,—by way of supporting the fuel shell directly upon the ash pan of the rotary producer in the absence of obstruction either to the free descent of ashes from said shell into said pan, or to the free sweep of an ash removing plow over the surface of said pan. Other and further objects and advantages of my invention are set forth hereinafter in the following detailed description thereof; in connection with said description, reference is made to the accompanying drawings, in which—

Fig. 1 is a vertical sectional view of the lower portion of a gas producer embodying my invention.

Fig. 2 is a plan view of the same, portions thereof being shown in a section taken in the plane of line 2—2, Fig. 1.

Fig. 3 is an enlarged sectional view taken on the plane of the line 3—3, Fig. 1.

Fig. 4 is a fragmentary view in side elevation, on an enlarged scale, showing details of the shell-supporting construction.

Like reference characters refer to like parts in the different figures.

The numeral 1 indicates the lower portion of a gas producing chamber, inclosed within a wall or shell 2 which constitutes the fuel containing section of the producer. The lower end of said shell is arranged, substantially as shown in the aforesaid Jefferies patent, to open into a concentric ash support or pan 3, having a horizontal bottom 4 and flaring walls 5. This pan 3, according to the usual practice, is supplied with water which is maintained at a level high enough to make a seal with the depending skirt 6 of shell 2, thereby to prevent the escape of gases through the annular space left between walls 5 and skirt 6 for the withdrawal of ashes.

As in the aforesaid Jefferies patent, the ash

pan 3 is rotatably supported and driven, the support being afforded by a plurality of rollers 7, (only one being shown) arranged in a circular series beneath a ring 8 on the bottom of said pan, and the drive being secured by a bevel pinion 9 in mesh with a bevel gear 10 on said ring 8. As set forth in the aforesaid Jefferies patent, rotation of the shell 2 in unison with the pan 3 is highly desirable, and moreover to avoid the complication and expense of independently supporting the shell for such rotation, said shell should have its support directly upon said ash pan, through connections which preserve an unobstructed space within said pan for the operation of an ash removing plow, indicated by the numeral 11.

These connections, in the aforesaid Jefferies patent, take the form of a plurality of hollow blast arms radiating from the center of the ash pan, and supporting on their outer ends an annular mantle on which the brickwork of the shell is erected; said hollow blast arms of Jefferies, lying wholly above the level reached by the sealing water contained in the ash pan, are frequently burned out by the intense heat of the surrounding incandescent fuel, and moreover, said hollow arms are of such thickness laterally that they offer undue resistance to the free descent into the ash pan of that portion of the mass of fuel and ash which is surrounded by the depending water seal skirt of the fuel shell; the tendency, in the operation of the Jefferies device, is for arches of clinkers to form across the segmental spaces of limited area left between the hollow blast arms, and these arches, which seriously impede the descent of ashes into the pan, must frequently be broken by hand-poking of the fire.

According to my invention, the above mentioned difficulties are overcome by the novel construction of the supporting connections between the ash pan 3 and the fuel section or shell 2. As shown in Fig. 1, a tube or sleeve 12 is secured by means of its annular base flange 13 to the center of ash pan bottom 4, with the passage through said tube forming a continuation of the central blast passage 14 of the producer, whereby the usual blast of

air, or air and steam, is conveyed upwardly to a distributing cap or cone 15 of ordinary construction, for discharge into the fuel bed by escape beneath the lower edges of said cap.

5 The tube or sleeve 12, as best shown in Fig. 2, is formed exteriorly with three pairs of longitudinally disposed ears or lugs 16, 16, these pairs of ears being spaced equidistantly on the circumference of said sleeve, and each pair providing, at the top and bottom, registering bolt apertures for the attachment of the arms 17, (three in number), that furnish support, as hereinafter described, for the shell 2.

10 Each arm 17 takes the form of a thin vertically disposed web, which gradually diminishes in height, by convergence of its upper and lower edges, from the maximum height at its inner end, corresponding substantially to the height of the sleeve 12. At 20 said inner end, each arm 17 fits snugly between a pair of ears 16, 16, and is held in place, at the top and bottom respectively, by suitable bolts 18 and 19, passing through the ear apertures and through corresponding apertures of said arm. Just above its upper bolt 18, each arm 17 provides an upstanding lug 20,—the three lugs 20 serving to support and center the blast cap 15 by their reception 25 in an annular recess 21 on the under side of said cap. From the lug 20, the upper edge of each arm 17, as thus secured to the sleeve 12, slopes sharply downward, so that the major portion of each arm 17, including the free outer end thereof, lies within the space 30 inclosed by the walls 5 of ash pan 3; thus in the operation of the producer, each arm 17 is almost wholly submerged in the water, used for sealing purposes, which fills said pan 3, giving ample protection against the burning out or distortion of the arms 17, 17, in spite 35 of the intense heat prevailing, because the heat of the unsubmerged upper portions of said arms is readily and rapidly conducted to the larger lower submerged portions, and absorbed by the surrounding water.

40 The refractory lining or brickwork of the shell 2 is erected upon an annular mantle 22 which is preferably angular in cross section and is provided with suitable stiffening webs 22'. The base portion 23 of said mantle 22 has three depending brackets 24, spaced equidistantly on its under surface, each bracket 24 having opposite lateral webs 25, 25, that 45 impart stiffness and rigidity to the intermediate spaced ears 26, 26, of said bracket, which ears at their lower ends receive between them the outer free end of the corresponding arm 17. Registering bolt holes in the ears 26, 26, and in the outer end of each arm 17 serve for the passage of bolts 27 for rigidly uniting the parts, and supporting the shell 2 upon the arms 17, which are in turn supported upon the ash pan 3, as above described. The webs 25, 25, of brackets 24, 24, have out-

wardly directed portions 28 to provide bearing surfaces against which the annular depending skirt 6 of shell 2 may be secured, as by rivets 29, 29.

5 In the above described construction, the desired action of the ash plow 11 is permitted to be carried out under the most favorable conditions, and at the same time the supporting arms 17, 17, which connect the fuel shell and the ash pan for rotation in unison, are so constructed and arranged as to leave the maximum space in the area inclosed by skirt 6, for the free descent of ashes into said pan. Moreover, the construction and arrangement of said arms 17, 17, submerges them, and especially from points of connection to the shell, in the water of said pan, whereby ample protection is secured against the necessity for frequent replacements of parts in the bottom portion of the gas producer. 85

I claim,

1. In a gas producer, a fuel-containing shell, open at its lower end, a rotary ash pan beneath said shell and in surrounding relation to the lower end thereof, said ash pan adapted to contain water for sealing the lower end of said shell, and connections for supporting said shell from said pan in the absence of obstruction of the bottom of said pan, said connections comprising arms radiating 90 from the center of said pan and connected at their outer ends to the seal-forming lower end of said shell, said arms being substantially submerged in the water contained in said pan, and said arms having their maximum dimensions in vertical planes to sustain the weight of said shell, and being relatively thin in cross section, thereby to minimize their obstruction of the open lower end of said shell. 100

2. In a gas producer, a fuel containing shell, a rotary ash pan beneath said shell, and providing a water seal for the lower end of said shell, a tubular member supported centrally of said ash pan to provide a blast outlet above the level of sealing water in said pan, and a plurality of arms radiating from said tubular member and connected at their outer ends to the submerged water-sealing lower end of said shell, said arms having major portions thereof submerged in the sealing water of said pan, and being relatively thin in cross section, thereby to minimize obstruction to the descent of ashes from said shell into said pan. 110
